BREAST AUGER T

Filed June 28, 1927

FIG. 1.

FIG. 2.

Inventor
Cornelius Eldon Holt

By

Robert Robb
Attorneys.

UNITED STATES PATENT OFFICE.

CORNELIUS ELDON HOLT, OF LEETONIA, OHIO.

BREAST-AUGER T.

Application filed June 28, 1927. Serial No. 202,128.

At the connection between a breast plate and a crank used to operate tools, breast auger T's are employed to afford a socket in which one end of the crank is seated. Heretofore, there has always been a large amount of friction at this point when the tool was operated, it being necessary, of course, to overcome this friction in the working of the tool.

10 The primary object of this invention is to provide a breast auger T which will eliminate to a large extent the friction between a crank and said T.

15 In carrying out the invention, there is provided in the T a ball which is loosely fitted therein and against which the crank bears.

20 This invention is further characterized by the seating of a ball in such a manner as to allow for lubrication thereof and removal of foreign matter from the interior of the T.

25 With these and other objects in view, as will in part hereinafter become apparent and in part be stated, the invention comprises certain novel constructions, combinations and arrangements of parts as subsequently specified and claimed.

In the accompanying drawings:—

30 Figure 1 is a perspective of a breast plate and tool with the improved auger T applied thereto.

Figure 2 is a detailed end view of the T shown in Figure 1 with the breast plate removed.

35 Figure 3 is a detailed side view of the T.

Figure 4 is a detailed end view of the crank.

40 In the accompanying drawings and specification, like reference characters denote corresponding parts throughout.

While the preferred form of the invention is herein set forth, it is to be understood that it is not to be limited to the exact construction set forth, because various modifications of these details may be provided in putting the invention into practice within the scope of the appended claim.

45 In the present embodiment of the invention there is shown the T 1 applied to a breast plate 2, for use in connection with a single crank 3 that operates an auger 4. It is to be understood, however, that this T may be used in any form of supporting plate, or with a suitable crank, either single or double, which is used to operate any of a wide variety of rotatable tools.

The breast plate 2, as shown in Figure 1, has the flanges 5 thereon to fit around the breast of a person, but this plate may be of any suitable design. One end of the crank, 60 noted by the reference character 6, fits in the breast auger T so that it may rotate therein. The novel construction of breast auger T eliminates to a large extent the friction that would ordinarily have to be 65 overcome in the operation of the tool. Any well known form of connection between the crank 3 and tool 4 may be employed.

The improved breast auger T comprises a main base or plate member 7 and a hollow 70 tubular portion 8 that is integral with the base portion. At each end of the base portions, openings 9 are provided in which fit bolts or rivets that are used to secure the T to the breast plate. The bore 10 of the tubular portion of the T is uniform throughout 75 most of its length. The bore 10 extends through the base portion of the T where it is enlarged, as shown at 11. Between the bores 10 and 11 there is the inclined shoulder 12. 80 The bore 11 is enlarged at the face of the base plate, as shown at 13. On the upper face of the base portion and intermediate the ends thereof, arched grooves 14 are provided. These grooves run from the side of 85 the base to the bore 11.

The ball 15 is loosely seated on the shoulder 12. It will be noted that if the ball be placed in the T and is then secured to a breast plate, that the ball will be held 90 securely in the T. The grooves 14 provide a means by which a lubricant may be forced into the bore of the T around the ball, as well as to permit of the removal of any foreign matter that may collect therein. 95

When the end portion 6 of the crank is fitted into the bore of the T it will bear against this ball. The end of this crank is hollow or cup-shaped, as shown in Figure 4. To secure the best results, however, it has been found that the end of the crank may be cut square and still a large reduction in the force necessary to overcome the friction will be obtained.

The bore 11 provides a recess for containing lubricant around the ball. It will be noted that as the ball is loosely fitted in the T that when the end of the crank bears against the ball it will be slightly unseated from the shoulder 12. Due to this unseating 110 and the movement of the ball, which is caused by the rotation of the crank, lubri-

cant will be supplied to that portion of the ball engaging the end of the crank. This supply of lubricant will be constantly replenished as the ball is moved around by the 5 crank. There is, therefore, always some lubricant between the end of the crank and the ball against which it bears.

Having thus described my invention, what I claim as new and desire to secure by Letters Patent of the United States, is:—

A breast auger $\mathbb{T}$ of the class described, comprising, in combination, a breast plate,

a $\mathbb{T}$ socket member rigidly fastened thereto, a bore through the $\mathbb{T}$ socket, said bore having an intermediate expanded portion, a 15 further enlarged portion adjacent the breast plate, a shoulder connecting the intermediate portion with the bore, a bearing in the intermediate portion and retained at all times by the shoulder and breast plate, and 20 openings in the $\mathbb{T}$ socket member communicating with the enlarged bores.

In testimony whereof I affix my signature.

CORNELIUS ELDON HOLT.
